US0D1023072S

(12) **United States Design Patent** (10) Patent No.: **US D1,023,072 S**
(45) Date of Patent: ** Apr. 16, 2024

(54) **WORK VEHICLE, TOY, OR REPLICA THEREOF**

(71) Applicant: **Deere & Company**, Moline, IL (US)

(72) Inventors: **Randy C. Rush**, Cedar Falls, IA (US);
Arlyn Wilcox, Grundy Center, IA (US);
Piyush Choudhary, Pune (IN);
Benjamin D. Dunnigan, Cedar Falls, IA (US)

(73) Assignee: **DEERE & COMPANY**, Moline, IL (US)

(**) Term: **15 Years**

(21) Appl. No.: **29/725,291**

(22) Filed: **Feb. 24, 2020**

(51) LOC (14) Cl. **12-09**

(52) U.S. Cl.

USPC **D15/23; D15/24**

(58) **Field of Classification Search**

USPC D15/10, 14-17, 22-26; 56/13.4, 13.3,
56/15.8, 15.9, 16.1, 16.7, 175, 202;

180/89.1, 89.12, 900; D14/492
CPC E02F 9/0841; E02F 3/3411; E02F 3/76;
E02F 3/34; E02F 3/00; E02F 7/00; B62D
21/186; B62D 53/028

(57) **CLAIM**

The ornamental design for a work vehicle, toy, or replica thereof, as shown and described.

DESCRIPTION

FIG. 1 is a perspective view of a work vehicle, toy, or replica thereof according to our new design;

FIG. 2 is a first end elevational view thereof;

FIG. 3 is a second end elevational view thereof;

FIG. 4 is a first side elevational view thereof;

FIG. 5 is a second side elevational view thereof;

FIG. 6 is a first plan view thereof; and,

FIG. 7 is a second plan view thereof.

The dashed lines in FIGS. 1-7 depict environment subject matter. The dashed lines form no part of the claimed design.

1 Claim, 7 Drawing Sheets
